FLOUR SIFTER

Frank R. Chester, Santa Monica, Calif.

Application September 29, 1949, Serial No. 5,221

Term of patent 7 years

(Cl. D44—29)

To all whom it may concern:

Be it known that I, Frank R. Chester, a citizen of the United States, residing at Santa Monica, in the county of Los Angeles, State of California, have invented a new, original, and ornamental Design for a Flour Sifter, of which the following is a specification, reference being had to the accompanying drawings, forming a part thereof, in which:

Fig. 1 is a perspective view of a flour sifter showing my new design; and,

Fig. 2 is a plan view thereof.

I claim:

The ornamental design for a flour sifter, substantially as shown.

FRANK R. CHESTER.
